DESIGN FOR A VACUUM CLEANER CASING

Ralph E. Kruck, Springfield, Mass., assignor to
Westinghouse Electric & Manufacturing Com-
pany, a corporation of Pennsylvania

Application April 6, 1938, Serial No. 76,320

Term of patent 7 years

To all whom it may concern:

Be it known that I, Ralph E. Kruck, a citizen of the United States, residing at Springfield, in the county of Hampden and State of Massachusetts, have invented a new, original, and ornamental Design for a Vacuum Cleaner Casing, of which the following is a specification, reference being had to the accompanying drawing forming part thereof, in which:

Figure 1 is a perspective view of a vacuum

cleaner casing, taken from the side, showing my new design;

Fig. 2 is a view in front elevation and Fig. 3 a view in side elevation of the vacuum cleaner casing shown in Fig. 1.

I claim:

The ornamental design for a vacuum cleaner casing substantially as shown.

RALPH E. KRUCK.
